JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

HANDLE FOR VACUUM CLEANERS AND SIMILAR APPLIANCES.

Application filed May 27, 1924. Serial No. 716,286.

To all whom it may concern:

Be it known that I, JOSEPH F. LAMB, a citizen of the United States, residing at New Britain, county of Hartford, State of Connecticut, have invented a certain new and useful Improvement in Handles for Vacuum Cleaners and Similar Appliances, of which the following is a full, clear, and exact description.

10 My invention relates particularly to handles for electric vacuum cleaners and similar appliances, of the type in which the electrical conducting cord for connecting the motor of the appliance with a lamp socket or other source of electrical supply leads out through an opening in the upper part of the handle. Heretofore, considerable difficulty has been experienced with the cord breaking at the point where it leaves the 15 handle, which is usually caused by the sharp bending movement of the cord at this point as the appliance is moved back and forth. Moreover, when the cord does break at this 20 point, it is very difficult to renew or repair 25 the same.

An object of the present invention is to provide means for reducing the liability of the cord breaking, the means being such that if a break occurs it will be at point where 30 the broken ends can be easily spliced or otherwise joined.

Another object of the invention is to provide a cord protecting device of the character indicated which is simple in construction 35 and easily applied to vacuum cleaners now in use.

The following is a description of an embodiment of my invention, reference being had to the accompanying drawings, in 40 which,

Figure 1 is a side elevation, partly broken away, of a portion of a vacuum cleaner handle embodying my invention in its preferred form;

45 Fig. 2 is a front view of the same;

Fig. 3 is a sectional plan view on an enlarged scale, taken on the line 3—3 of Fig. 1; and

50 Fig. 4 is a detail side elevation partly in section of the portion of the handle illustrated in Fig. 3.

The handle illustrated in the drawings, which is of a type commonly employed on

vacuum cleaners, comprises a tubular rod 2 having a hand grip 4 on its upper end. 55 The electric motor of the appliance is adapted to be connected with a lamp socket or other source of electrical supply through the usual flexible conductor having insulated wires 6 and 8 that lead from the motor up 60 through the handle rod, one of them being connected to switch contacts (not shown) located on the inside of the rod near its upper end, and leading from the switch and having their outer ends connected with a 65 lamp socket plug. The usual block upon which the switch members are mounted, extends out through an opening in the wall of the handle rod and is secured by screws 10 to a supporting plate 12 that covers said 70 opening and is secured by screws 14 to the outer side of the rod. The switch is adapted to be operated, to make and break the motor circuit, by means of a finger operated lever 16 that extends outwardly through a 75 clearance slot in the cover plate 12. The wires 6 and 8 are suitably insulated and are twisted together, and the two are covered by a braided covering so as to form a cord 18. This cord leads out from the switch through 80 an eyeleted opening 20 in the cover plate 12, and adjacent to the plate 12 extends through a tightly coiled spring 22, the inner end of which extends a distance through the opening 20 and is suitably held therein. 85

The handle is also provided with two cord hooks 24 which are spaced one above the other a considerable distance apart and the upper one is spaced a distance below the lower end of the cover plate 12, the cord 90 hooks being for the purpose of permitting the cord to be wound thereon in the usual manner when the appliance is not in use. As usual, the cord hooks are made of sheet metal and are provided with lugs 26 which 95 partially embrace the handle rod and are secured thereto. The upper cord hook 24 is secured to the handle by means of a bolt or pin 28 which extends through apertures in the lugs 26 and wall of the handle rod 100 2, and is provided with a collar or head 30 engaging one of the lugs, and a nut 32 screw-threaded on its other end engaging the other lug so as to firmly clamp the lugs against the rod, the pin being extended from 105 the head 30 and bent to form a hook 34

from which the dust bag of the cleaner may be hung. The lower cord hook is secured to the handle by means of a rivet 35 extending through apertures in the lugs 26 and the wall of the handle rod.

Heretofore, the conducting cord leading from the handle has hung loosely from the opening 20 where it leaves the handle, with the result that it was slatted or swung back and forth as the appliance was moved back and forth, and the consequent sharp bending of the conductors adjacent said opening resulted in frequent breakage thereof. In the illustrated construction, however, by means embodying my invention the cord is held from bending movement at said point where it leaves the handle and the cord is otherwise protected. To provide for this, in applying the upper cord hook 24, the portion of the cord adjacent the plate 12 is first pulled down close to the handle rod and then the back of the hook is laid against the cord and attached to the rod, as above described. The back of the hook is shaped to provide a longitudinal groove 37 through which the cord passes, and the groove is of suitable size to cause its wall to hold the cord against the handle rod, and thus hold the portion of the cord between the hook and eyelet opening 20 and the coil spring 22 down near to the handle rod, the tension of the spring 22 keeping this portion of the cord tight.

Also mounted on the handle rod a short distance below the upper cord hook 24 is a bracket member or clamp 36. This bracket member comprises a sheet metal strap having an intermediate strap or band portion embracing the rod, and having its end portions directed forwardly to provide forwardly projecting lugs or arms 38 that are arranged substantially parallel and spaced apart. The marginal portions of the arms 38 are extended and bent outwardly to provide reinforcing ribs or shields 39. The bracket strap is caused to grip the handle rod by means of a clamping screw bolt 40 that extends through apertures 42 in the arms 38 near their inner ends, and is further held in position on the rod by means of a bent-in projection 44 in its back portion that fits into an aperture in the wall of the handle rod. The arms 38 are provided with horizontal key-hole-shaped slots 46 that form continuations of the clamping bolt apertures 42, and have their reduced end portions directed toward the outer ends of the arms. The reduced portions of these slots 46 receive the ends of a pin or stud 48. This stud is secured in position in the slots 46 by the engagement of the arms 38 with shoulders 50 on the stud, the clamping bolt 40 causing the arms to firmly clamp the shoulders between them. The stud is provided with heads 52 on its ends that are

of slightly greater diameter than the width of the reduced portions of the slots 46. In applying the stud 48, it is inserted through the enlarged portion of the key-hole slot 46 in one of the arms, and is then brought forward to cause the reduced portions of its ends to be received in the reduced portions of the two slots 46, after which the bolt 40 is inserted and tightened to firmly hold the stud in place, as well as to cause the bracket strap to firmly grip the handle rod as above described. It will be apparent that upon loosening or removing the clamping bolt 40, the stud 48 may be removed.

The cord 18 extends downwardly from beneath the upper cord hook 24 through the space between the stud 48 and the clamping bolt 40, then outwardly and up over the stud 48, and then downwardly again through the space between the stud and the clamping bolt, the cord being thus looped about the stud. In thus looping the cord 18 about the stud 48, the clamping bolt and stud are removed; a loop is formed in the cord and this looped portion of the cord is positioned between the bracket arms 38 opposite the enlarged portions of the key-hole slots 46, and then the stud is inserted through the slots, and through the loop and is brought forward into the reduced portions of the slots, the clamping bolt 40 being then inserted and tightened. It will be apparent that the cord looped about the stud 48 may be thus applied to and removed from the bracket member without threading it through any opening, thus making disconnection of either of its ends unnecessary. When the cord is in place and the bolt 40 is inserted it holds the pin 48 in outward position. The pin 48 can, therefore, only be removed when the bolt 40 is entirely removed.

It will be apparent that during the use of the appliance, the portion of the cord extending between the upper cord hook and the eyeleted opening 20 is held from any bending movement, so that there is no danger of this portion breaking either at the opening 20 or at any other point. It will also be apparent that all the pull on the cord comes on the cylindrical stud 48, and there are no square or sharp corners to break the cord. In case the cord should in time break, the break of course would occur adjacent the stud 48, and if this should happen, the broken ends may, upon removing the stud, be easily spliced and taped between the clamp and the upper cord hook, the cord being then looped and the stud being slipped through the loop and clamped in position as hereinbefore described. The mounting of the loop holding stud, whereby it may be easily removed and replaced without removing the clamp from the handle rod, enables such repairing of the cord to be easily done.

As will be evident to those skilled in the

art, my invention permits of various modifications without departing from the spirit thereof or the scope of the appended claims.

What I claim is:

- 5 1. The combination with a handle of an electrically operated appliance of the class described having an electrical conducting cord passing longitudinally through said handle leading out through an aperture in
- 10 10 the upper part of the handle for connecting the motor of the appliance with a source of electrical supply, of a cord holding device mounted on the handle and spaced a distance below said aperture for holding a portion
- 15 15 of the cord adjacent to said aperture and between said source and aperture from bending movement while the appliance is in use.
- 20 2. The combination with a handle of an electrically operated appliance of the class described having an electrical conducting cord passing longitudinally through said handle leading out through an aperture in the upper part of the handle for connecting the motor of the appliance with a source of
- 25 25 electrical supply, of means comprising a member mounted on the handle a distance below said aperture over which the cord is looped for holding a portion of the cord adjacent to said aperture and between said
- 30 30 aperture and said source from bending movement while the appliance is in use.
- 35 3. The combination with a handle of an electrically operated appliance of the class described having an electrical conducting cord passing longitudinally through said

handle and leading out through an aperture in the upper part of the handle for connecting the motor of the appliance with a source of electrical supply, of cord holding means comprising a support mounted on the handle 40 a distance below said aperture having laterally projecting lugs provided with keyhole slots and a member having its ends detachably mounted in the keyhole slots in said lugs over which the cord is looped between 45 said lugs, and a bolt passing through said lugs between said cord and said handle and blocking the movement of said pin.

4. The combination with a handle of an electrically operated appliance of the class 50 described having an electrical conducting cord passing longitudinally through said handle and leading out through an aperture in the upper part of the handle for connecting the motor of the appliance with a source 55 of electrical supply, of cord holding means comprising a strap embracing said handle and having its end portions projecting laterally therefrom, a member over which the cord is looped adjacent to said aperture and 60 at a point between said aperture and said source having its ends detachably mounted in apertures in said end portions, and detachable means for causing said end portions to grip said member between them and 65 said strap to grip said handle, said member being removable and having shoulders acting to space said ends.

JOSEPH F. LAMB.
